W. Taylor.

Dear Mr.
Irvin C. Bowman

Inventor:

George Maurer,
Baldwyns, Newington Niles,
Att'g

UNITED STATES PATENT OFFICE.

GEORGE MAURER, OF CHICAGO, ILLINOIS.

KNIFE-SHARPENER.

1,324,512.

Specification of Letters Patent.

Patented Dec. 9, 1919.

Application filed December 8, 1917. Serial No. 206,261.

To all whom it may concern:

Be it known that I, GEORGE MAURER, a subject of the King of Hungary, (and who has taken out his first papers for citizenship 5 in the United States,) residing at Chicago, in the county of Cook, and State of Illinois, have invented a new and useful Improvement in Knife-Sharpener, of which the following is a specification.

10 My invention relates more particularly to knife-sharpener provided of a form adapting them to be carried in the pocket of a garment, as for example by waiters or others using knives, though certain features 15 thereof may be incorporated in a device intended to be supported on a table or wall.

20 My objects are to provide a novel, simple, and economical construction of knife-sharpener, preferably in a form to be carried about in the pocket of a user and by which 25 a knife may be quickly sharpened to present the desired fineness of edge and in which the bodies of abrasive or cutting material provided may be quickly removed and replaced at will.

25 Referring to the accompanying drawing Figure 1 is a face view of my improved knife-sharpener showing it as completely opened up to disclose details of construction, the position shown being one not assumed by the device in use, and with the means for restraining the opening of the device, disconnected. Fig. 2 is a top view of the device showing it in operative position but with certain parts shown in disconnected condition. Figs. 3 and 4 are sections taken at the broken lines 3-3 and 4-4, respectively, on Fig. 2 and viewed in the direction of the arrows; and Fig. 5, an end 40 view of the device in folded condition in which it is adapted to be carried about in the pocket of a garment.

The device comprises a casing constructed of a pair of hollow, preferably substantially 45 rectangular members 5 and 6, which may be of metal, and side sections 5^a and 6^a. The members 5 and 6 are hingedly connected together on the pintle 8 which passes through ears 9 on the sections 5 and 6, a coiled spring 50 10 surrounding the pintle between these ears and bearing at its opposite ends 11 against the inner faces of the sections 5 and 6, operating to swing the sections 5 and 6 in a direction away from each other on their 55 hinge connection. The opposite sides of the sections 5 and 6 are equipped with the

sections 5^a and 6^a which complete the closure, these sections being secured to the sections 5 and 6 by squared removable and replaceable pins 7 which pass through ears 60 12 and 12^a on these sections, the openings in these ears being square to prevent rotation of the sections 5^a and 6^a on the carrying sections 5 and 6.

Secured to, and located in the interior of, the sections 5 and 6 are a series of knife-sharpening sections 13 to 16 inclusive, each series being shown as formed of four of the sections though the number thereof may be varied as desired. The knife-sharpening 70 sections are arranged in the casing to extend preferably at a right angle to the axis of the hinge connecting the sections 5 and 6 together and the knife-sharpening sections of one series thereof are staggered relative to the knife-sharpening sections of the other series thereof, as shown in the drawings. The knife-sharpening sections referred to of each series range from one producing a relative coarse cut to one which produces 80 a relative fine smoothening cut with the others graduated in between, those of the knife-sharpening sections bearing similar numerals, producing the same degree of abrading or sharpening action on the knife. 85 By preference the knife-sharpening sections 13 would be steels of a character commonly used in the sharpening of carving knives, the sections 14 would be relatively coarse sharpening stones, the sections 15 relatively finer sharpening stones, and the sections 16 still finer sharpening stones to produce the desired smoothness of edge on the knife. 90

The knife-sharpening sections are held in 95 place in the covers 5 and 6 by engagement at dove-tailed portions 17 thereof with pairs of inclined flanges 18 formed on the strips 19 secured to the inner faces of the cover sections 5 and 6 as by soldering them thereto, 100 this feature of the construction permitting the knife-sharpening sections to be readily slipped into and out of the channels provided between the pairs of flanges 18 and when in position therein be held firmly in 105 the desired position relative to each other. It is preferred that the surfaces of the sections 14, 15, and 16 with which the knife-blade contacts in the sharpening operation, be rounded as shown, to augment the abrading or sharpening action, and that the sections 13 which preferably extend a slight 110

distance, as for example 1/100 of an inch short of the plane in which the sharpening surfaces of the other sections extend, be slightly flattened as indicated at 13^a.

5 In the use of the device, the sections 5 and 6 are opened, as for example to the position shown in Fig. 3, to present a channel into which the knife-blade to be sharpened is inserted, it being preferred that some restraining means, as for example the chain illustrated at 20 and connected with studs 21 on the inner faces of the sections 5 and 6, be provided for preventing the sections from swinging an undue distance apart under the 10 action of the spring 10. The operator grasping the device with the hinge portion thereof lying in his palm and with the sections 13 extending adjacent the thumb portion of his hand, introduces the knife-blade to be 15 sharpened into the channel shown at 22 in Fig. 3 and draws it toward him while maintaining the cutting edge of the blade in engagement with the knife-sharpening sections, it being preferred that the operator 20 in this drawing operation referred to gradually press the sections 5 and 6 toward each other, causing the knife-blade to rise in the channel 22 as it becomes progressively shallower.

25 30 In the use of the device as preferably constructed as above stated, the operator by varying the pressure exerted by him at the end of the case containing the sections 13 may bring these particular sections into and out of position for contacting with the knife-blade by reason of the flexibility of the case and thus may sharpen the blade on all of the sections, or only those other than the sections 13, as desired.

35 40 It will be noted that the portions of the knife-blade will be first acted on by the relatively coarse sharpening sections 13 when in position to act on the knife, thence by the next finer sections 14 and so on throughout 45 the series and thus the knife will be sharpened very effectually, causing it to present the desired finished edge.

When the device is out of use, the operator closes the sections 5 and 6 together and 50 fastens them in this position by the snap-fastener 23 on the section 6^a engaging a hook 24 on the section 5^a.

To remove the sharpening sections the operator withdraws the pins 7 permitting the 55 sections 5^a and 6^a to be removed and then slides the sharpening sections out of the grooves containing them.

What I claim as new and desire to secure by Letters Patent is—

60 1. In a knife-sharpener, the combination of a plurality of series of knife-sharpening surfaces arranged in staggered relation and presenting a V-shaped channel into which the knife-blade to be sharpened is inserted 65 for contacting said surfaces, the surfaces of

said series being graduated from a relatively coarse sharpening surface to a relatively fine sharpening surface, whereby as a knife-blade is drawn through said channel its cutting edge portion is progressively 70 acted upon by the graduated knife-sharpening surfaces, first producing coarse sharpening and finally relatively fine sharpening.

2. A knife-sharpener comprising a casing formed of hingedly-connected sections, a 75 plurality of series of knife-sharpening surfaces in said casing arranged in staggered relation with said surfaces angularly disposed relative to the axes of said hinge and presenting a V-shaped channel into which 80 the knife-blade to be sharpened is inserted for contacting said surfaces, said casing being open along one side for removal and replacement of said surfaces therethrough, and a closure for said open side of the 85 casing.

3. A knife-sharpener comprising a casing formed of hingedly-connected sections, spring means tending to swing said sections apart, a plurality of series of knife-sharpening surfaces in said casing arranged in staggered relation with said surfaces angularly disposed relative to the axes of said hinge and presenting a V-shaped channel into which 90 the knife-blade to be sharpened is inserted for contacting said surfaces, said casing being open along one side for removal and replacement of said surfaces therethrough, a closure for said open side of casing, and means for limiting the opening of 100 said sections under the action of said spring means.

4. A knife-sharpener comprising a casing formed of hingedly-connected sections, spring means tending to swing said sections 105 apart, a plurality of series of knife-sharpening surfaces arranged in staggered relation with said surfaces angularly disposed relative to the axes of said hinge and presenting a V-shaped channel into which the knife-blade to be sharpened is inserted for contacting said surfaces, said casing being open along one side for removal and replacement of said surfaces therethrough, a closure for the open side of said casing, and releasable 115 means engaging said closure for holding the parts of said casing including said closure, in closed position against the action of said spring means.

5. A knife-sharpener comprising a casing 120 formed of hingedly-connected sections, a plurality of series of knife-sharpening surfaces in said casing arranged in staggered relation with said surfaces angularly disposed relative to the axes of said hinge and presenting a V-shaped channel into which 125 the knife-blade to be sharpened is inserted for contacting said surfaces, said casing being open along one side for removal and replacement of said surfaces therethrough, 130

and a closure for said open side of the casing formed of sections and means for releasably securing said sections to said hingedly-connected sections.

5. 6. In a knife-sharpener, the combination of a plurality of series of knife-sharpening surfaces arranged in staggered relation and presenting a V-shaped channel into which the knife-blade to be sharpened is inserted 10 for contacting said surfaces, said surfaces at the portions thereof contacted by the knife being of curved contour, the surfaces of said series being graduated from a relatively coarse sharpening surface to a relatively fine 15 sharpening surface, whereby as a knife-blade is drawn through said channel its cutting edge portion is progressively acted upon by the graduated knife-sharpening surfaces, first producing coarse sharpening and finally 20 relatively fine sharpening.

7. In a knife-sharpener, the combination of a plurality of series of knife-sharpening surfaces arranged in staggered relation and presenting a V-shaped channel into which 25 the knife-blade to be sharpened is inserted for contacting said surfaces, the surfaces of said series being graduated from a relatively coarse sharpening surface to a relatively fine sharpening surface, and means supporting 30 said surfaces, the coarsest of said surfaces being inset from a plane in which the remainder of said surfaces extend, said means supporting said surfaces being constructed and arranged as to permit the operator at

will to extend said coarse surfaces into position for engaging with the blade as it is drawn through said channel. 35

8. In a knife-sharpener, the combination of a plurality of series of knife-sharpening surfaces arranged in staggered relation and 40 presenting a V-shaped channel into which the knife-blade to be sharpened is inserted for contacting said surfaces, the surfaces of said series being graduated from a relatively coarse sharpening surface to a relatively fine 45 sharpening surface, and means supporting said surfaces, the coarsest of said surfaces being inset from the plane in which the remainder of said surfaces extend, said means supporting said surfaces being constructed 50 and arranged as to permit the operator at will to extend said coarse surfaces into position for engaging with the blade as it is drawn through said channel, and the portions of said coarse sharpening surfaces adjacent the knife-blade being flat. 55

9. In a knife-sharpener, the combination of a casing formed of hingedly-connected sections and knife-sharpening members on said casing-sections arranged in staggered 60 relation and presenting a V-shaped channel, when said casing is open, into which the knife to be sharpened is inserted for contacting said sharpening members, means carried by said sections to normally hold 65 the same in open position, said casing forming a complete housing for said members.

GEORGE MAURER.
